TOY TOWER CONSTRUCTION

Joseph L. Bonanno, Madison, N. J., assignor to
 The Lionel Corporation, New York, N. Y., a corporation of New York

Application August 16, 1946, Serial No. 690,898

4 Claims. (Cl. 46—12)

1

The present invention relates to towers for toy water tanks.

The present invention contemplates towers for toy water tanks wherein the towers are so made as to closely simulate the appearance of towers for the water tanks commonly employed along a railroad right of way.

According to the present invention, such towers employ a base simulating the appearance of the base of the usual water tower, plastic or molded lattice elements which support a base for the water tank. These parts are held together by a central tie preferably in the form of a tube which while simulating the supply pipe for the usual water tower, is available to carry wiring up to concealed operating apparatus and provide a grounded return circuit.

The accompanying drawings show, for purposes of illustrating the present invention, an embodiment in which the invention may take form, it being understood that the drawings are illustrative of the invention rather than limiting the same.

In these drawings:

Figure 1 is a side elevational view of the tower for toy water tank;

Figure 2 is a top plan view of the same with parts broken away and shown in section along the line 2—2 of Figure 1;

Figure 3 is a vertical sectional view taken on the line 3—3 of Figure 2; and

Figure 4 is a perspective view illustrating two of the lattice work members.

The tower employs a base 10 which is here shown as having the contour of a Greek cross. This base is preferably in the form of a die casting and has twelve column footing simulating elements 11, each with square upwardly opening recesses 14 and central holes or perforations 15. At the center the base has an internally threaded tubular riser 16.

The base for the water tank is shown at 20. As shown it is in the form of a plastic disk, made for example from polystyrene. This molding has a thin upper portion 21 below which are found sleeper simulating elements 22 which appear to be carried on the top of sill forming elements 23. The molding 20 has a central opening 24 to accommodate a metal tube 25 adapted to tie the parts together. The sill forming members 23 are provided with slots 26 which serve to lighten the molding and provide receptacles for pins 27 carried on the upper ends of the lattice members 28.

These lattice members shown more clearly in Figure 4, are in the form of molded elements.

2

It requires twelve of these lattice elements to make up a toy water tower. Each element has a comparatively heavy column forming member 29, diagonal brace simulating elements 30, horizontal tie elements 31 and a thin vertical element 32. The latter is parallel with the element 29 and is connected to the cross braces 30 and horizontal tie elements 31.

The column forming element 29 of the lattice 10 is slotted as indicated at 33 to receive the thin side element 32 of the adjacent lattice. The lower end of this heavy column element 29 is provided with a pin 34.

These lattices are symmetrical end for end 15 and may be reversed so that the two lattices may form an inside corner as indicated at A, Figure 2, or an outside corner as indicated at B, Figure 2. The dimensions of the lattice molding are such that the pins 34 and 27 will fit into either 20 of the holes 15 in the base or the ends of the slots 26 in the tower base plate 20. In this fashion the lattice members can all be held in a definite location and will simulate the appearance of a number of structural columns 25 connected by diagonal and horizontal braces such as would be used in a structural steel tower. The tube 25 is threaded into the riser 16 in the metal base of the tower and a nut 35 threaded on the upper end of this tube may be employed to hold the assemblage together.

The base 10 supports two binding posts 40 and 41, one of which may be grounded to the base casting and through the central tube 25 and plate 43 under the nut 35, provide a return connection for electrical apparatus grounded to the plate. The other binding post 40 may be connected by a wire 44 which extends up through the tube 25.

Since it is obvious that the invention may be embodied in other forms and constructions within the scope of the claims, I wish it to be understood that the particular form shown is but one of these forms, and various modifications and changes being possible, I do not otherwise limit myself in any way with respect thereto.

What is claimed is:

1. In a toy lattice work assemblage, a plurality of substantially identical molded elements, each element having a column portion provided with a longitudinally extending groove, a brace forming part extending away from the column part at an angle to the groove, and a connector parallel with the column part and connecting the brace forming parts, the connector being re-

ceived in the groove of an adjacent column part, and top and bottom plates to secure the upper and lower ends of the said molded elements in position.

2. In combination in a toy, two substantially flat, skeleton framing units, each having a lattice in one plane, the lattice comprising a thick element down one side, a thin element down the other side, and diagonal braces and horizontal tie elements between the side elements, the thick element having a longitudinal slot extending at an angle to said plane and adapted to receive the thin element of another of said lattices, the two skeleton framing units being assembled to form a corner by positioning the thin element of one unit in the longitudinal slot in the other unit.

3. A toy support comprising a cover member having a central opening, a plurality of relatively thick, wide sill-simulating elements depending from said cover member, and a plurality of relatively thin shallow sleeper forming elements depending from said cover member and positioned at right angles to said sill forming elements, the sill forming elements having downwardly opening sockets, a base having upwardly opening recesses spaced the same as the said sockets in the cover member and a central opening, columns having lower ends in the recesses and thin upper ends in the sockets, and a tie means extending through and connecting the central openings of said cover member and said base.

4. In a toy tower simulating the appearance of a structural steel tower, a base, a superstructure, a plurality of identical, unitary, molded elements, each having a thick edge member forming an upwardly extending corner post for the tower and a panel forming a side for the tower, said side being formed of narrow integral braces forming a lattice and terminating in a thin bar, the thick edge having a longitudinal groove extending laterally therefrom and at an angle to said panel, into which groove the thin bar of an adjacent molded element enters so that the braces appear to interconnect the cornerposts, and means securing the base, the superstructure and molded elements together.
